Primary Examiner — John A Voytek(74) *Attorney, Agent, or Firm* — Robert N. Lipcsik; June E. Rickey(57) **CLAIM**

The ornamental Design for a tire, as shown and described.

DESCRIPTION

FIG. 1 is a perspective view of a tire showing our new design, it being understood that the pattern repeats uniformly throughout the circumference of the tread;

FIG. 2 is a front elevational view thereof;

FIG. 3 is a right side elevational view thereof; the left side elevational view being identical thereto; and,

FIG. 4 is an enlarged fragmentary front elevational view thereof taken along line 4-4 of FIG. 2.

The dashed broken lines indicating an enlargement portion of the design form no part of the claimed design.
